FUSE

Philip S. Williams and Ben W. Sewell, Tulsa,
Oklahoma, assignors to the United States of America
as represented by the Secretary of the Navy

Application January 15, 1946, Serial No. 641,342

1 Claim. (Cl. 102—79)

1

This invention relates to a fuze, and more particularly to a fuze for use with armor piercing projectiles.

One object of the invention is to provide a fuze for use with armor piercing projectiles which is maintained in safe condition until impact of the projectile with the target, whereupon the fuze becomes cocked and thereafter fires only after the deceleration forces, sometimes called reverse setback forces, drop to a predetermined value.

Another object of the invention is to provide a fuze which is especially adapted for use in projectiles fired against concrete pill boxes in which it is desirable that the projectile be detonated only after it has penetrated as far as possible into the target.

Another object of the invention is to provide a fuze of the type referred to above which is simple and positive in operation, and which is easily produced in large quantities.

These and other objects of the invention will be evident from the following specification and the accompanying drawings, in which

Fig. 1 is a longitudinal sectional view of the fuze in safe condition prior to firing of the projectile from a gun;

Fig. 2 is a longitudinal sectional view of the fuze taken during flight of the projectile;

Fig. 3 is a longitudinal sectional view of the fuze taken after impact of the projectile with the target but before firing of the fuze;

Fig. 4 is a longitudinal sectional view of the fuze after maximum penetration of the target, showing the fuze elements in their firing positions; and

Fig. 5 is a graph showing, by a solid curved line, the snap action characteristic of the resilient means employed, the deflection vs. load characteristic of conventional spring means being shown by a dotted line.

In the preferred embodiment of the invention shown in the drawings, the fuze comprises a hollow outer body member 10 having internal shoulders 11 and 12. The forward end of the body member 10 is provided with a pair of diametrically opposed radial bores 13 in which are mounted a pair of detent housings 14 closed at their outer ends and containing centrifugal detents 15 which are urged inwardly by coil springs 16. The outer ends of the bores 13 are staked at 17 to retain the detent housings 14 in place.

The rear end of the body member 10 is inwardly flanged at 18 to retain a disc-shaped member 19 having an axial bore 20 which contains a percussion detonating charge 21 for detonating the

2

main explosive charge of the projectile with which the fuze is used. The member 19 is retained against forward movement relative to the body member 10 by means of a washer 22 which is positioned between the shoulder 11 and the member 19, and which has an inwardly extending flange 23 which serves to define the limit of forward movement of an inertia member 24 positioned within the housing by means of its co-operation with an external flange 25 on the rear end of the inertia member.

The inertia member 24, with the exception of its flange 25, is of a smaller outer diameter than the inner bore of the flange 23 and has a forwardly extending hub 26 of diminished diameter to fit within the opening defined by shoulder 12 in the forward portion of the body member 10 adjacent the bores 13. The rear surface of the inertia member 24 is provided with an axial recess 27 in which is mounted a thin metal washer 28 by means of a retainer ring 29 which is held in place by an inwardly extending flange 30 on the inertia member. Resilient means comprising a plurality of resilient washers 31 of the "Belleville" type are mounted on the hub 26 of the inertia member between the forward surface of the inertia member and the shoulder 12 of the body member so as to urge the inertia member rearwardly toward its initial position as shown in Fig. 1.

The inertia member 24 is provided with an axial bore 32 in which is positioned a firing pin 33 having a disc-shaped head 34 on its forward end, the head having an outer diameter approximately equal to that of the hub 26. The rear end of the firing pin 33 is formed with a shoulder 35 and a pointed detonator contacting portion 36 which initially is positioned within the central opening in the washer. The diameter of the firing pin and the diameter of the opening 28a in the washer 28 are such that the washer 28 initially abuts the shoulder 35 of the firing pin when the inertia member is in its initial position and thereby prevents rearward movement of the firing pin.

In operation, with the elements of the fuze in their unarmed positions as shown in Fig. 1, the inertia member 24 is retained in its initial position by the resilient washers 31 and by the abutment of the forward end of the hub 26 with the centrifugal detents 15 which also abut the head 34 of the firing pin to prevent rearward movement of the firing pin. The shoulder 35 at the rear end of the firing pin is in contact with the disc 28 which alone is of sufficient strength to

retain the firing pin against rearward movement except as will be explained presently.

When the projectile provided with the fuze is fired from a gun, the rotation of the projectile during flight sets up centrifugal force which acts on the detents 15 and throws them outwardly into the positions in which they are shown in Fig. 2 so that they no longer lie in the path of rearward movement of the firing pin head 34 and also are out of the path of forward movement of the hub 26 of the inertia member 24. During the flight of the projectile, the inertia member 24 is retained in its initial position by the resilient washers 31 which oppose any tendency of the inertia member to move forward under the small forces of reverse setback which arise as the projectile slows down during its flight through the air. The engagement of the washer 28 with the shoulder 35 on the rear end of the firing pin 33 prevents rearward movement of the firing pin to a firing position.

Upon impact of the projectile with a target such as a concrete structure, the immense forces of reverse setback which act upon the elements of the fuze immediately upon contact causes the inertia member 24 to overcome the resistance of the resilient washers 31 and move forwardly until the forward end of the hub 26 lies against the rear surface of the head 34 of the firing pin. The forward movement of the inertia member also carries the washer 28 forwardly over the shoulder 35 of the firing pin to the position shown in Fig. 3, bending the margin of the opening in the washer rearwardly.

As soon as the forces of deceleration or reverse setback decrease below a predetermined value as the projectile comes to a stop, the resilient washers 31 move the inertia member 24 rearwardly and due to the grasping of the firing pin 33 by the bent marginal portion of the opening in washer 28, the firing pin is moved rearwardly with the inertia member into firing contact with the detonator 21 to detonate the projectile.

It is desired particularly to emphasize that the "Belleville" type washers 31 are employed for the resilient means for the reason that they have a peculiar snap action characteristic, as indicated by the solid line and curve in the graph of Fig. 5. A coil compression spring has a straight line deflection vs. load characteristic, as indicated by a dotted line on said graph for comparison. Thus, when reverse set-back reaches a predetermined minimum value, the firing pin 33 is immediately

thrown with considerable force into the detonating charge 21.

It is obvious that the present invention provides an efficient fuze for armor piercing projectiles which detonates the projectile only after the projectile has substantially decreased its forward movement after impact with the target.

It is to be understood that there is herein described a preferred embodiment of the invention and that the invention is susceptible of numerous variations therefrom without departing from the spirit of the invention as defined by the appended claim.

What is claimed is:

15 In a fuze for use with rotating projectiles, a firing pin having firing and safe positions, an inertia member having an unarmed position and an armed position to which it is movable by forces of reverse setback, resilient means resisting movement of said inertia member out of said unarmed position under the influence of reverse setback forces smaller than a predetermined magnitude, means normally positively retaining said firing pin and said inertia member in said safe position and said unarmed position, respectively, said last named means being movable to an inoperative position by centrifugal force incident to rotation of the projectile in flight, and means carried by said inertia member for retaining said firing pin in a safe position while said inertia member is in its unarmed position and for snapping said firing pin to its firing position upon movement of said inertia member to its armed position and subsequent return of the inertia member to its unarmed position under the influence of said resilient means after the force of reverse setback diminishes below said predetermined magnitude, said last mentioned means consisting of a plurality of stacked resilient washers.
